UNITED STATES PATENT OFFICE.

CHARLES W. MONROE, OF BAY CITY, MICHIGAN.

DESIGN FOR AN AIR-MOISTENER.

SPECIFICATION forming part of Design No. 16,783, dated July 6, 1886.

Application filed May 26, 1886. Serial No. 203,338. Term of patent 7 years.

To all whom it may concern:

Be it known that I, CHARLES W. MONROE, a citizen of the United States, residing at Bay City, in the county of Bay and State of Michigan, have invented and produced a new and original Design for Air-Moisteners; and I do declare the following to be a full, clear, and exact description of the same, reference being had to the accompanying drawing, forming a part thereof.

The figure represents a perspective view of an air-moistener made according to my design.

The mechanical features of the device are fully set forth in an application of mine filed February 20, 1886, Serial No. 192,716.

In the annexed illustration, the letter A indicates the cover, B the base, and C the

reservoir. The reservoir C resembles a bundle of cigars, *c* representing the individual cigars, and *c'* the ribbon with which they are tied. The top is cylindrical and the base circular, with its exterior reversely curved, as shown.

I claim—

The design for air-moisteners herein shown and described, the same consisting in a reservoir resembling a bundle of cigars tied with a ribbon, and a cover and base of substantially the shape shown.

In testimony whereof I affix my signature in presence of two witnesses.

CHARLES W. MONROE.
